UNITED STATES PATENT OFFICE.

AUGUST H. MARSCH, OF CHICAGO, ILLINOIS.

CLASP.

SPECIFICATION forming part of Letters Patent No. 793,888, dated July 4, 1905.

Application filed March 13, 1905. Serial No. 249,837.

To all whom it may concern:

Be it known that I, AUGUST H. MARSCH, a citizen of the United States, and a resident of Chicago, in the county of Cook and State of Illinois, have invented certain new and useful Improvements in Clasps; and I do hereby declare that the following is a full, clear, and exact description thereof, reference being had to the accompanying drawings, and to the letters of reference marked thereon, which form a part of this specification.

This invention relates to a clasp for corsets and other uses designed to prevent disconnection of the interlocking parts of the clasp and consequent unfastening of the parts joined thereby, except when the parts are intentionally manipulated in a manner to effect their separation.

The invention consists in the matters hereinafter described, and pointed out in the appended claims.

In the drawings, Figure 1 is a face view of parts of two corset-steels provided with a clasp made in accordance with my invention. Fig. 2 is a cross-section taken on line 2 2 of Fig. 1. Fig. 3 is a perspective view of the body of the clasp removed from the steel. Fig. 4 is a sectional view taken on line 4 4 of Fig. 2. Fig. 5 is a cross-section of the clasp, taken on line 5 5 of Fig. 1. Figs. 6 and 7 are side views of modified forms of clasps embodying the principal features of my invention.

As shown in the said drawings, A and B indicate two corset-steels, such as are usually secured in the front edges of the two parts of a corset. The steel A is provided with a slotted sheet-metal loop member C, and the steel B with a headed stud D, adapted for detachable engagement with the loop member. Said loop member C is secured by rivets to the steel A and projects therefrom toward the steel B in the usual manner. Said loop member is, moreover, provided with a keyhole-slot to receive the stud D, said slot having at its end nearest the steel A an enlarged part or hole E, adapted for the passage of the head of the stud D and having its outer end made narrower than the head of the stud and adapted to receive the shank of the stud.

Referring first to the form of loop member shown in Figs. 1 to 5, the same consists of a piece of sheet metal much longer than the loop member and having its end portion folded back upon itself beneath and parallel with the main part of the loop member and slotted to form two arms C' C', adapted to extend at the sides of the stud D when the latter is engaged with the narrower outer part E' of the slot. The loop member is made of metal so thin as to have a considerable degree of elasticity or resiliency, so that the ends of the arms C' C' are adapted to yield toward the body of the loop member when pressure is brought on said arms. The body of the loop member is, moreover, outwardly bent between the steel A and the outer or narrower part E of the slot, so as to form elevated parts or humps C² C² in its parts at the sides of the slot thereon. Said elevated parts or humps C² C² are so located with respect to the enlarged part E and narrow extension E' of the slot that when the stud is engaged with the said narrow extension its head will stand adjacent to the outwardly-facing inclined parts or shoulders of the humps and cannot be shifted into the enlarged part of the slot without the passage of its head over the said humps. The arms C' C' being below and parallel with the body of the loop member, they are in position to bear or press against the steel B when the loop member is engaged with the stud, and thereby hold the body of the loop member outward and in contact with the head of the stud. When the stud is in the narrower outer end of the slot and the loop member is held against the head of the stud by the action of the spring-arms C' C', as described, the elevations or humps C² C² will stand in the path of the head of the stud and prevent the stud from being shifted or moved inwardly along the slot to the enlarged part E thereof, and thus becoming disengaged from the loop member. If, however, the loop member be pressed toward the steel B at the same time that it is moved endwise toward the stud, the arms C' C' will bend or yield toward the body of the loop member, thereby permitting the elevations or humps C² C² to be depressed or moved toward the steel B.

far enough to permit them to pass beneath the head of the stud. The same effect will be produced if the steels be pressed toward each other with sufficient force to effect the downward bending or depression of the body of the loop member through the action of the inclined faces of the humps $C^2 C^2$ on the under surface of the head of the stud. The said elevations or humps $C^2 C^2$, in connection with the spring-arms $C' C'$, therefore serve to hold or lock the parts of the clasps from movement in a direction to effect the release of the loop member from the stud, while at the same time the parts may be disconnected by applying force or pressure to the parts of the clasp in a manner to depress the part of the loop member bearing the said humps toward the steel B, thereby enabling said humps to pass beneath the said head on the stud. In joining the parts of the clasp the same operation is performed, the head of the stud being first inserted through the enlargement E when it will stand at the rear of the humps $C^2 C^2$, and the clasp will then be pressed toward the steel B and at the same time moved in a direction to carry the stud into the outer or narrower part of the slot, or the same effect will be produced by drawing the steels apart with sufficient force to carry the humps $C^2 C^2$ past or beneath the head of the stud. In order to prevent the ends of the spring-arms $C' C'$ from catching in the cloth which covers the steel B or in articles of clothing with which the clasp may come in contact, the extremities of the said arms have outwardly bent or curved parts $c c$, which extend into the outwardly-bent parts of the loop member by which the humps $C^2 C^2$ are formed. Said parts $c c$ are preferably adapted to bear at their ends on the inner faces of said humps $C^2 C^2$ and to slide thereon as the arms $C' C'$ yield toward the body of the loop member when the humps are forced or carried beneath or past the head of the stud.

In Fig. 6 is shown a form of clasp in which the parts are reversed and the humps on the spring-loop member are adapted to engage the steel to which the stud is attached instead of the head of the stud. As shown in said Fig. 6, A and B indicate the steels, and D a stud on the steel B, as before described. In this instance F indicates the loop member, which is like that shown in Figs. 1 to 5, but has its backwardly-bent arms $F' F'$ extended along its outer face in position for contact with the head of the stud, while the humps $F^2 F^2$ are formed in the body of the loop member and project toward the steel B and are adapted for contact therewith when the loop member is moved toward the stud to carry the latter into the enlarged inner part G from the outer narrower part G' of the slot in the loop member. The ends of the arms $F' F'$ are provided with inwardly-

bent parts $f f$, which extend into contact with the inwardly-bent parts $F^2 F^2$ of the loop member and are thereby adapted to readily pass beneath the head of the stud when brought into contact with the same in the act of engaging the loop member with the stud.

In Fig. 7 a loop member H is shown, having a slot in its body part provided with an enlarged inner part and a narrower outer part, as before. The loop member in this instance has a backwardly-bent part extending outside of the body of the loop member and slotted to form two spring-arms $H' H'$, as in the form of clasp shown in Fig. 6. In this instance, however, the said arms H' are provided near their inner or free ends with outwardly-bent parts or humps H^2 , which are adapted to act on the head of the stud in the same manner as the humps $C^2 C^2$. (Shown in Figs. 1 to 5.)

I claim as my invention—

1. A clasp comprising a stud member having a headed stud and a loop member consisting of a body part having a stud-receiving slot which is closed at both ends, and is enlarged at its inner end for the passage of the head of the stud, said body part being extended at its outer end to form an end portion which is folded inwardly over the body portion and slotted to form two spring-arms located at the sides of the slot in the body portion, and the free ends of which are directed toward the inner end of the body portion and are free to yield toward said body portion, said loop member having at the sides of the slot therein, between the narrower outer and enlarged inner ends thereof, outwardly-bent parts or humps which stand normally in position to yieldingly resist the movement of the stud member along said slot into and out of the narrower outer end thereof.

2. A clasp comprising a stud member having a headed stud and a loop member consisting of a body part having a stud-receiving slot which is closed at both ends and is enlarged at its inner end for the passage of the head of the stud, said body part being extended at its outer end to form an end portion which is folded inwardly over the body portion and slotted to form two spring-arms located at the sides of the slots in the body portion, and the free ends of which are directed toward the inner end of the body portion and are free to yield toward said body portion, said body portion having at the sides of the slot therein, between the narrower outer and enlarged inner ends thereof, outwardly-bent parts or humps which stand normally in position to yieldingly resist the inward movement of the stud member along said slot into and out of the narrower outer end thereof.

3. A clasp comprising a stud member and

a loop member provided with a slot enlarged at its inner end to receive the head of the stud and the end portion of which is folded upon the body of said loop member and slotted to form spring-arms, said loop member being provided at the sides of the slot therein with outwardly-bent parts or humps, and the free ends of said arms being bent toward the body of the loop member opposite said outwardly-bent parts or humps.

4. A clasp comprising a stud member and a loop member provided with a slot to receive the stud enlarged at its inner end for the passage of the head of the stud, and the end portion of which is folded upon the body of the loop member and slotted to form two spring-arms adapted to extend at opposite sides of the shank of the stud and to bear against the steel to which the stud is attached, the body of the said loop member being provided at opposite sides of the slot therein with outwardly-bent parts or humps, and the ends of the said spring-arms being bent outwardly and adapted to enter the outwardly-bent parts of the body forming said humps.

5. A clasp comprising a stud member and

a loop member provided with a slot to receive the stud enlarged at its inner end for the passage of the head of the stud, and the end portion of which is folded upon the body of the loop member and slotted to form two spring-arms adapted to extend at opposite sides of the shank of the stud and to bear against the steel to which the stud is attached, the body of the said loop member being provided at opposite sides of the slot therein with outwardly-bent parts or humps, and the ends of the said spring-arms being bent outwardly and adapted to enter the outwardly-bent parts of the body forming said humps.

In testimony that I claim the foregoing as my invention I affix my signature, in presence of two witnesses, this 10th day of March, A. D. 1905.

AUGUST H. MARSCH.
